UNITED STATES PATENT OFFICE.

DAVID LEVY, NEW YORK, N.Y.

FLY-PAPER HOLDER.

Application filed November 22, 1921. Serial No. 517,059.

To all whom it may concern:

Be it known that I, DAVID LEVY, a citizen of the United States, and a resident of the city of New York, borough of Bronx, in 5 the county of Bronx and State of New York, have invented a new and Improved Fly-Paper Holder, of which the following is a full, clear, and exact description.

This invention relates to improvements in 10 fly paper holders, an object of the invention being to provide improved means for supporting a roll of fly paper in such a manner that there is no danger of a person becoming entangled in the paper.

15 A further object is to provide means for supporting a roll of paper and for manually feeding the roll after the exposed portion thereof has served its purpose.

The common form of fly paper sheets or 20 hanging strips have proven very inconvenient to use, and another object of this invention is to provide means for supporting a roll of fly paper in such a manner that it may either serve the function of a sheet, or 25 it may be suspended upon the wall to serve the purpose of the ordinary hanging strip.

A still further object is to provide a holder 30 which will be simple and practical in construction, strong, durable and efficient in use, neat and attractive in appearance, and comparatively inexpensive to manufacture.

With these and other objects in view, the invention consists in certain novel features of construction and combinations and arrangements of parts as will be more fully hereinafter described and pointed out in the claims.

In the accompanying drawings:

Figure 1 is a view in side elevation of my 40 improved holder;

Figure 2 is a plan view thereof; and

Figure 3 is an enlarged broken view on the line 3—3 of Figure 2.

Referring in detail to the drawings, I have 45 used the reference numeral 1 to designate a boxlike frame which includes side walls 2, end walls 3 and a bottom 4, the frame being open on top whereby it presents a substantially trough-shaped structure. This frame 50 is preferably formed of wood or other material which lends itself to economy of manufacture.

It will be noted that the side walls of the frame are of increased height adjacent each 55 end, as indicated at 5, and that aligned slots 6 are provided in the upper edges of the side

walls adjacent their ends. It will be seen that these slots are curved at their inner ends for a purpose which will be hereinafter apparent. In one pair of slots 6, a shaft 7 is 60 mounted. This shaft is preferably square in cross section and includes reduced ends 8, circular in cross section and having annular grooves 9 therein forming reduced portions which fit within the slots 6 and serve to provide rotary mounting for the shaft. 65

At the other end of the frame a rewinding core 10 is provided. This core is also formed with annular reduced ends 11, which are further reduced, as indicated at 12 to fit 70 within the other pair of slots 6. The core 10 is also square or angular in cross section and a relatively large disc 13 is fixed to the core adjacent one end thereof within the frame. A similar disc 14 is loosely mounted on the 75 other side of the core. These discs not only serve to facilitate the manual turning of the core, but also serve to guide the rewinding of paper upon the core.

I have indicated at 15 a cartridge reel having 80 a hollow square core 16, upon which a plurality of convolutions of paper 17 are wound. This paper is preferably gummed upon one face. The free end of the paper also carries a square tube 18 of cardboard or 85 other relatively stiff material.

In using the apparatus, the shaft 7 is removed from the box, inserted within the core 16 and then replaced in its mounting. The paper is partially unwound from the reel, the core 10 is removed from the box or frame, the disc 14 is detached from the core, and the tube 18 is slipped over the core. The disc 14 may then be replaced and the core 10 then 90 restored to its normal position. In order to feed paper from the cartridge reel on to the rewinding core it is merely necessary to manually turn the discs 13 and 14. After a number of flies have been entangled upon the strip of paper exposed between the shaft 7 and the rewinding core, the paper may be 95 rewound concealing the flies thereon and exposing a fresh gummed portion. It will also be noted that when the frame is used in the horizontal position shown in the drawings, 100 any flies which may succeed in crawling off the paper will fall into the box or frame. If it proves more convenient to do so, the frame may be suspended from a suitable support, a flexible device 19 being provided for this 105 purpose at one end of the box. When the paper carrying frame is in suspended posi-

tion, the curved inner ends of the slots 6 prevent the paper from falling out of the frame.

Although I have illustrated one of the preferred embodiments of my invention, it will be obvious that various slight changes and alterations might be made in the general form and arrangement of the parts described without departing from the invention, and hence I do not wish to limit myself to the precise details set forth, but shall consider myself at liberty to make such slight changes and alterations as fairly fall within the spirit and scope of the appended claims.

I claim:

1. A holder for a strip of fly paper, comprising a frame open at the top and presenting a substantially trough-shaped structure, said frame having the side walls thereof of greater height at each end than at the center, said side walls at the ends being formed with openings, a rotatable member arranged in each of said openings, a spool mounted on

one of said rotatable members, said spool being adapted to carry a coiled supply of fly paper, a connecting member secured to one end of said supply of fly paper adapted to connect said fly paper with the other of said rotatable members, and manually actuated means for rotating the last mentioned rotatable member, said manually actuated means acting as a guide for guiding said paper whereby it may be wound on the last mentioned rotatable member.

2. A fly paper holder, comprising a container open at the top, a shaft rotatably journaled at one end thereof, a reel mounted on said shaft, said reel being adapted to contain a coiled strip of fly paper, a square tube connected with one end of said fly paper, a square shaft rotatably mounted in the opposite end of said frame and extending through said square tube, and manually actuated guiding disks mounted on said square shaft whereby said tube may be rotated and the fly paper wound thereon.

DAVID LEVY.
